W. M. COURSON

SHOE HEEL STIFFENER

Filed Aug. 17, 1922

Patented May 29, 1923.

1,456,915

UNITED STATES PATENT OFFICE.

WILLIAM M. COURSON, OF TRAVERSE CITY, MICHIGAN.

SHOE-HEEL STIFFENER.

Application filed August 17, 1922. Serial No. 582,486.

To all whom it may concern:

Be it known that I, WILLIAM M. COURSON, a citizen of the United States, residing at Traverse City, in the county of Grand 5 Traverse and State of Michigan, have invented certain new and useful Improvements in Shoe-Heel Stiffeners; and I do declare the following to be a full, clear, and exact description of the invention, such as 10 will enable others skilled in the art to which it appertains to make and use the same.

This invention relates to an improved stiffener for use in connection with the heel portion of a shoe and one object of the invention is to provide a stiffener which may be put in place and may serve to stiffen and brace the heel portion of a high or low-quarter shoe and may also serve as a heel pad.

20 Another object of the invention is to provide a stiffener which is so constructed that the heel pad portion which rests directly above the heel of the shoe may fit snugly in place and thus cause the shoe to be comfortable with the stiffener in place.

Another object of the invention is to so construct this stiffener that it may be either secured within the shoe by nails which will be driven down into the heel portion of the 30 shoe or if so desired left free and simply held within the shoe by the pressure of the heel portion of the foot.

Another object of the invention is to so construct this stiffener that the vertically 35 disposed portion which engages the rear portion of the upper may conform to the contour thereof to brace this portion of the upper and keep it in the proper shape and to further so construct the upper end portion of this vertically disposed portion of the brace that there will be no danger of the upper edge portion causing scraping which would injure the foot of the wearer.

Another object of the invention is to so 45 construct this brace that the body portion thereof may be formed from sheet metal stamped and then bent to assume the desired shape.

This invention is illustrated in the accompanying drawing, wherein:

Figure 1 is a perspective view showing the shoe in dotted lines and the attachment in full lines.

Figure 2 is a central vertical longitudinal 55 sectional view of the improved device.

Figure 3 is a vertical transverse sectional view taken along the line 3-3 of Fig. 2.

Figure 4 is a vertical longitudinal sectional view through the attachment showing a slightly modified construction.

This improved brace is to be used in connection with a shoe S and will be positioned in the rear portion thereof so as to brace the rear portion of the upper and further provide a heel pad. This shoe brace is provided with a body portion which is formed of sheet metal stamped out to provide a base portion 1 and a tongue extension 2 which has its inner or lower end portion reduced to permit of easy bending and permit the tongue 2 to extend upwardly and brace the rear portion of the shoe upper. The brace has been shown in connection with a high shoe but as previously stated, it can be readily used in connection with a low-quarter shoe as well as a high shoe. The base portion of this brace is flat and curved and tapered rearwardly to conform to the contour of the heel portion of the shoe and upon this flat face will be provided a pad 75

3 which conforms to the contour of the base and will be formed of leather or any other suitable material. This pad may be secured to the base 1 by rivets 4 as shown in Fig. 4 or it may be secured by nails 5 which will be passed through the pad and through openings formed in the base and driven down into the heel H of the shoe. In the form shown in Figs. 1, 2 and 3, the brace will be firmly mounted in 90

the shoe by means of the nails 5 but in the form shown in Fig. 4, this brace will be left loose in the shoe and may be readily removed and placed in another pair of shoes when so desired. The vertically disposed tongue 2 is curved transversely so that it will conform to the transverse contour of the rear portion of the shoe for snug engagement with the same. The vertically disposed tongue will therefore serve to retain the rear portion of the shoe upper in the proper shape and prevent it from working out of the proper shape. The upper end portion of this tongue is bent to extend rearwardly as shown at 6 so that the foot 95

may be readily inserted without danger of catching against the upper edge of the tongue. It will be further noted that this prevents the upper edge of the tongue from scraping and tearing the stocking and caus- 105

ing a sore to be formed upon the foot. The side edge portions may also be bent slightly to extend rearwardly as shown at 7 to prevent the side edges of this tongue from 5 scraping and causing injury to the stocking and foot. It will thus be seen that the device may serve in a very efficient manner to brace the rear portion of the upper and prevent it from getting out of shape and 10 further that the device will also serve as a heel pad for the shoe. It should also be noted that the device may be either firmly anchored in the shoe by means of the nails which will be driven down into the heel or 15 they may be placed loosely in the heel portions of the shoe and simply held in place by pressure of the foot. When the device is simply placed in the shoe and not secured, it is only necessary to lift the devices out when 20 it is desired to put them in another pair of shoes, but when it is desired to transfer the form shown in Figs. 1, 2 and 3 from one pair of shoes to another, it is necessary to either first remove the nails or else grasp 25 the device by the tongue 2 and draw it upwardly so that the nails will be drawn

out of the shoe. The forward end portions of the leather pad 3 and base portion 1 will be tapered as shown at 8 in Fig. 2 to prevent this forward edge from having a tendency to scrape and injure the stocking and heel. The device can therefore be very comfortably worn in the shoe and will be very effective in operation.

I claim:

A shoe brace for fitting within the rear portion of a shoe, said brace being formed from a sheet metal blank including a base forming portion and a tongue forming portion, said blank being reduced intermediate 40 its length and bent transversely at the reduced portion to provide a base conforming to the contour of the heel portion of a shoe and an upwardly extending tongue portion extending upwardly from the rear end of 45 the base, said tongue being curved transversely and having its sides and upper edge portions bent to extend rearwardly.

In testimony whereof I have hereunto affixed my signature.

WILLIAM M. COURSON.
